UNITED STATES PATENT OFFICE

FLORENT HINNEKENS, OF PATERSON, NEW JERSEY, ASSIGNOR TO VAN VLAANDEREN MACHINE COMPANY, OF PATERSON, NEW JERSEY, A CORPORATION OF NEW JERSEY

DYEING MACHINE

Application filed August 14, 1925. Serial No. 50,264.

This invention relates to that class of dyeing or equivalent machines in which the material to be treated is placed in a casing containing the liquid and agitated by rotary motion 5 around a horizontal axis and back and forth. My invention has two principal objects, one, to provide improved automatic means for obtaining the back and forth rotary motion, and the other, to provide for such supporting of 10 the rotated element that, as in the case where access to the material being treated from time to time must be had, said element may be elevated at such times so as to disestablish the driving connection.

15 In the drawing—

Fig. 1 is a front elevation of the improved machine;

20 Fig. 2 is a side elevation, partly in section; and

25 Fig. 3 is a diagram of electrical circuits which may be used when the source of power is an electric motor.

The said element is here represented by the 30 horizontal rotary shaft 1 which may carry so as to rotate therewith in the usual way a reel on which to suspend the material being treated and contained in the casing or tank 2, which is fragmentarily shown in Fig. 2 by broken lines, the reel itself being not shown.

35 3 is a stand which affords bearings at 3^a for the horizontal main shaft 4 equipped between the bearings with a worm 4^a. With this worm engage the teeth of the worm-wheel 5 which is arranged over the worm and fixed on shaft 1, forming part of said element. For disestablishing the connection between the worm and worm-wheel the shaft 1 is supported as follows:

40 At the end portion of said shaft adjoining the worm-wheel is a bearing 6 formed with a partly spherical portion 6^a which in effect forms the ball of a ball-and-socket joint of which the socket is afforded by the interiorly 45 spherical upstanding part 7 of the head of a screw 8 which is swivelled in a bearing 9. This bearing has a depending flange 10 which is vertically slotted as shown by dotted lines in Fig. 1 to receive clamping screws 11 tapped 50 into an upstanding part 12 of the stand 3, whereby after elevating is effected through

the medium of the screw 8 the bearing may be held fast in the position to which it is elevated. At the time said element is being driven the bearing has solid support on the top of part 12.

The part 12 is essentially a box-formation on the back of the stand 3, having a limited opening 12^a at the back and bottom. At its base it affords support for a ball-bearing 13 on which rests a nut 14 which is penetrated and engaged by the threads of the screw 8 and is exteriorly formed as a worm-wheel. In horizontally aligned bearings 15 projecting from the rear of the box is journaled a worm-shaft 16 having a worm 16^a in mesh with the worm of the nut. This has a hand-wheel 17 by turning which and consequently the screw 8 up and down movement of the mentioned element may be effected. The object in forming the bearing at 6 of the ball-and-socket type is to allow the shaft 1 to assume angular relation to the axis of part 7 in the up and down movement effected through the screw and nut, it being understood that the end portion of the shaft remote from the worm-wheel 5 has a bearing, as 18, affording a fulcrum-support therefor, as by being somewhat free to articulate therein. The box-formation 12 serves as a housing for the nut worm-wheel and worm 16^a. To house the engaging portions of worm 4^a and worm-wheel 5 the stand has a well 19 open at the top and backed by the box-formation.

The main shaft 4 is geared with a driving shaft 22 journaled in stand 1 and adapted to be rotated alternately in opposite directions, the gearing being the worm-wheel 24 and worm 25. Shaft 22 is connected to rotate with the shaft 20 of an electric motor M by a suitable coupling 23. For obtaining rotation of the driving shaft first in one and then in the other direction, alternately, the motor is reversed. Any circuit arrangement including the motor may be used for accomplishing this, and Fig. 3 will serve as an example, in which 26 is a circuit containing the generator G for energizing the motor M and a pole-changer 27 whose bar 27' may form the common armature of two electro-magnets 28, and 29 is a circuit having an energy source 30

and, in each branch, one of the magnets and also a break 31 to be closed by a button or other circuit-closer 32, appearing also in Fig. 1. When either button is pushed the corresponding magnet will be energized to shift the pole-changer and so cause reversing of the motor.

To the front vertical web 33 of the stand 3 is bolted the bracket 34 having a horizontal platform 35. This platform and the button-casings 32' guide vertically a pair of controlling devices 36 respectively arranged over the buttons and cushioned in their downward movement by springs 37 interposed between the casings and collars 36' on said devices. Said devices yieldingly oppose rocking in either direction of an actuator itself including portions cushioned against movement in either direction of the rocking relatively to each other and constructed as follows: The platform 35 has a front boss 38 in which is fixed a rearwardly projecting stub-shaft 39. On this is fulcrumed between its ends the lever 40 having rollers 41 at its ends to bear on said devices; also the upstanding lever 42 which projects into the path of an eccentric abutment on worm-wheel 5 afforded by the roller 43, the end of the lever being double-beveled to receive the contact of the abutment. Lever 40 forms one and lever 42 the other of the said portions of the rocking actuator. Rods 44 are pivoted to the end of the lever 42 and they project freely through holes in bosses 45 swivelled in the ends of lever 40, and between the bosses and collars 46 on the rods are compression springs 47.

Assume the intergeared parts 1-5, 4 and 22 to be a rotary system revoluble back and forth and having the motor as its rotary prime mover. Each time the abutment engages lever 42 of the rocking structure the latter rocks and depresses, according to the direction in which the rocking is occurring, one of the devices 36; this in turn will depress the corresponding button and cause to be energized the corresponding magnet which will shift the pole-changer and so reverse the motor and said system. If for any reason the reversing should not ensue the lever 42 can nevertheless yield to the pressure of the abutment until the latter passes; there is thus provision for avoiding injury to the machine possible in the event that the controlling circuit 29 is not closed and especially in view of the ponderous nature of the rotary system.

Having thus fully described my invention what I claim and desire to secure by Letters Patent is:

1. In combination, with a rotary system revoluble back and forth and having a rotary prime mover and an eccentric moving abutment, means to reverse the direction of rotation of the prime mover including a pair of cushioned controlling devices, and a rocking actuator for the controlling devices pro-

jecting into the path of rotary movement of said abutment and having its rocking in one direction yieldingly opposed by one and in the other direction by the other of said devices.

2. In combination, with a rotary system revoluble back and forth and having a rotary prime mover and an eccentric moving abutment, means to reverse the direction of rotation of the prime mover including a pair of cushioned controlling devices, and a rocking actuator for the controlling devices having an impact-receiving portion arranged in the path of rotary movement of said abutment and a portion whose rocking is yieldingly opposed by said devices, said portions being elastically connected with each other and the impact-receiving portion being yieldable relatively to the other portion in each direction of rocking said structure.

3. In combination, with a rotary system revoluble back and forth and having a rotary prime mover and an eccentric moving abutment, means to reverse the direction of rotation of the prime mover including a pair of cushioned controlling devices, and a rocking actuator for the controlling devices including an impact-receiving rocking lever arranged in the path of movement of said abutment, another rocking lever whose rocking is yieldingly opposed by said devices, and cushioned means interposed between the levers and opposing rocking of the first lever independently of the second lever.

In testimony whereof I affix my signature.

FLORENT HINNEKENS.
